UNITED STATES PATENT OFFICE.

ALWORTH SEWEL, OF BERRYVILLE, ARKANSAS.

FIRE-ALARM.

SPECIFICATION forming part of Letters Patent No. 359,694, dated March 22, 1887.

Application filed April 14, 1886. Serial No. 198,552. (No model.)

To all whom it may concern:

Be it known that I, ALWORTH SEWEL, a citizen of the United States, residing at Berryville, in the county of Carroll and State of Arkansas, have invented a new and useful Improvement in Fire-Alarms, of which the following is a specification, reference being had to the accompanying drawings.

My invention relates to improvements in fire-alarm devices, and the novelty consists in the construction, arrangement, and combination of the several parts comprised therein, substantially as hereinafter described, and specifically pointed out in the claims.

In the drawings, Figure 1 represents a plan view of a fire-alarm embodying my improvements. Fig. 2 is a front elevation thereof, and Fig. 3 is a central sectional view on the line *xx* of Fig. 1.

Referring to the drawings, in which similar letters of reference denote similar parts, *A* designates an automatic fire-alarm device.

A' designates the frame thereof, consisting of a transversely-extending sill, *a*, provided at its opposite ends with uprights *a'*, connected together at their tops by a timber, *a''*, the ends *a''* of which project at each side beyond the uprights *a'* at each side of the frame.

B and *B'* designate timbers secured in a horizontal plane to the uprights *a'*, near the bottoms thereof and transversely of the machine.

C and *C'* designate shafts journaled in boxes *c* upon the projecting portions of the timbers *B* and *B'*, at each side of the uprights *a'*, one of which shafts projects at one end beyond the outer surface of the timber *B*, and is provided with a crank, *c'*, for a purpose hereinafter described. Each of said shafts *C* and *C'* is provided at one end within the timber *B'* with a spur-gear wheel, *D* and *D'*, the teeth of which engage. (See Fig. 3.)

E and *E'* designate flat bars that project through apertures *e*, formed through the shafts *C* and *C'*, near the middles thereof. These flat bars or plates are carried by the rotary shafts, and are adapted to alternately strike the vibrating hammers of the bell to sound the alarm, and on one of its side edges the bars or plates are provided with a series of notches or recesses, into one of which takes the free end of latch *f*. One of these latches is provided for each of the operating-plates, and they are pivoted on and carried by the rotary shafts in their

movements. The notched arms or plates *J* are adjustably secured to the rotary shafts, so that they can be extended beyond the same for a greater or less distance, to permit them to draw the vibrating hammers of the bell to a greater or less distance away from the bell, and vary the force with which the hammer strike the bell to correspondingly vary the intensity of the sound emitted thereby. Thus it will be seen that when one of the plates is adjusted farther from the shaft by which it is carried, it will draw the vibrating hammer with it farther away from the bell than when the plate is shortened, so that the hammer will be impelled toward the bell with greater velocity when released by the arm or plate, and consequently strike the bell with more force. The bars *E* and *E'* are arranged to alternately strike the vibrating spring-actuated bell-hammers *F*, secured within a bell, *G*, and depending from the timber *a''* of the frame *A'*.

H designates a cord that is at one end wound upon the shaft *C*, and extends thence over a pulley secured at any convenient point—as for instance, the overhanging end of a timber *I*, secured to the timber *a''*—to a weight, *h*, for the purpose of giving rotary motion to said shaft *C*.

h' designates a cord attached at one end to the crank *c'*, and extending thence to point in a building exposed to fire, for the purpose hereinafter described.

K designates a pawl pivoted at one end to the sill *a*, and engaging the teeth of one of the gear-wheels *D*, when desired.

The operation of my invention is as follows: The weighted cord *H*, being wound upon the shaft *C*, is temporarily held from unwinding by the engagement of the pawl *K* with the teeth of the wheel *D*. The cord *h'* is now passed through a loop or staple, *h''*, on the end of the timber *a''*, and extended to the desired point at which it is to be secured, after which the pawl *K* is released from the wheel *D*, said cord *h'* now operating to prevent rotation of the shaft *C*. By severing or cutting the cord *h'*, in the event of a fire, the rotary shafts, which are geared together for simultaneous operation, will be driven by the descent of the weight and the consequent uncoiling of the cord *H* on one of the shafts. The operating arms or plates *E* and *E'* are rotated with the shafts

and alternately strike the vibrating hammers of the bell, to insure a constant ringing alarm.

It will be seen that the rotary geared shafts are held under tension for immediate operation by the cord and the weight attached thereto, and the shafts are prevented from rotating by the cord *h'*, whereby, when the latter is cut or severed, the weight descends to rotate the shafts simultaneously and actuate the vibrating hammers to sound the alarm.

My invention can also be adapted to serve as a burglar-alarm. In this adaptation the cord *h'* is connected or secured to the door, window, or other place which it is desired to protect and the detent *K* withdrawn from the gear-wheel of one of the shafts, so that they are then controlled by the weighted cord. When the door or window is forced open or the cord cut, the strain or pull exerted by the cord on one of the shafts is released, to permit the said shaft to rotate under the descent of the weight, as will be very readily understood.

I claim—

1. In an automatic fire alarm, a frame, *A'*, having timbers *B B'* secured thereto, and shafts *C C'*, journaled therein and provided with bell-clapper-striking bars *E E'*, said shafts being geared together and provided with means for rotating them, in combination with a bell, *G*, and the spring-clappers *F* thereof, substantially as described.

2. The combination of the rotary shafts geared together for simultaneous operation, the adjustable plates carried by the shafts, a

bell, the vibrating hammers arranged in the path of the plates, a cord connected to one of the shafts to retard the rotation thereof, and means for revolving the shafts when the cord is released, substantially as described.

3. The combination of a rotary shaft moving a crank, an adjustable plate carried by the shaft, a bell, a vibrating hammer therefor arranged in the path of the plate, a cord connected to the crank of the shaft, and means for rotating the shaft when the cord is released, substantially as described, for the purpose set forth.

4. In an automatic alarm of the class described, the combination of the rotary shafts geared together for simultaneous operation, a crank secured to one of the shafts, the notched plate fitted on the shaft, a latch for adjustably connecting the said plate to its shaft, a cord connected to the crank, a detent for retaining the shafts against the rotary movement, means for revolving the shafts when the cord and detent are released from the crank and shafts, a bell, and the vibrating hammers therefor arranged in the path of the plates on the shafts, all arranged and adapted for service, as herein described.

In testimony that I claim the foregoing as my own I have hereto affixed my signature in presence of two witnesses.

ALWORTH SEWEL.
